UNITED STATES PATENT OFFICE

JOHN PHILLIP GRILLI AND HARRY L. WETHERBEE, OF CHICAGO, ILLINOIS, ASSIGNORS
TO H. A. BRASSERT & COMPANY, OF CHICAGO, ILLINOIS, A CORPORATION OF
ILLINOIS

CHECKERWORK

Application filed July 15, 1929. Serial No. 378,279.

This invention relates to a new and improved checkerwork for regenerators, and more particularly to checkerwork especially adapted for use in connection with hot blast

5 stoves of the types used with blast furnaces.

Hot blast stoves or the like consist of shells which are filled with brick checkerwork, the function of the brick being to absorb heat from the products of combustion coming 10 from the blast furnace or similar metallurgical furnace, and to give up heat to the air to be used in blasting the furnace.

The efficiency of a hot blast stove, or similar regenerative apparatus depends primarily 15 upon the efficiency of the heat transfer. For a given volume of heat absorbing brick, the greater the surface exposed to the hot gases or to the cold air, the more efficient is the transfer of the heat from the heated gases to 20 the brick and in turn the transfer of heat from the heated brick to the cold air going toward the furnace. It is essential that the passages for flow of gas and air be so proportioned as to bring about proper contact 25 between the brick surfaces and the heated gases and the cold air in order that heat may be transferred to and from the brick.

According to the construction of the present invention rectangular brick are used to 30 build up the body of the checkerwork, these brick being laid in such way that square openings or flues are formed extending vertically through the checkerwork. Each course of rectangular brick is preferably laid to break 35 joint with the courses above and below it. Rectangular brick of different sizes are used in certain of the courses so that in these courses lateral openings are provided which afford communication between certain of the 40 adjacent vertical flues. In one course there may be communication between flues adjacent each other in one direction and in another course communication between flues adjacent at right angles to the previously mentioned lines of communication.

This communication afforded between vertical flues is of importance in that it permits the equalization of pressures in the flues and 45 also permits a by-passing of gases or air so that an entire flue will not be lost to use if

an obstruction occurs in it. The gases or air can by-pass such an obstruction and return to the blocked flue at a later point of cross communication.

In the preferable form of construction, diagonally extending filler brick are placed in the vertical flues in at least the lower portions of the structure. These filler brick afford an increased heat transfer surface together with an increased volume of heat absorbing material. The fillers also help to brace the rectangular bricks and to maintain the uniformity of the vertical flues. The filler brick may be of different sizes in different vertical sections of the checkerwork so as to maintain 55 an approximately uniform velocity of the gases flowing through them. The gases or air are hottest at the top of the checkerwork and here the filler brick may be omitted. The volume of the gases or air is less in lower 60 portions of the stoves where temperatures are lower and here the filler brick may be of increased size. The filler brick are preferably 65 so placed in the checkerwork as to break joint vertically with the rectangular main checkerbrick which assists in maintaining the stability of the structure and the prevention of lateral displacement of one course of brick on another, with consequent blocking of the vertical flues. The filler brick also render the 70 accurate laying up of the main checkerbrick 75 more easy and further assist in holding them in position under the strains due to the changes in temperature throughout the heat transfer cycle.

It is an object of the present invention to provide a new and improved checkerwork especially adapted for use in hot blast stoves or the like.

It is a further object of the invention to 80 provide a construction having vertically extending flues and so designed as to provide cross communication between adjacent flues.

It is an additional object to provide a construction in which the several brick used 85 break joint both vertically and horizontally whereby the stability of the structure is maintained.

It is also an object to provide a structure 90 consisting of rectangular brick serving to 95

form the main flues, with additional filler brick located in the flues.

It is a further object to provide an efficient heat transfer structure which is composed of simple units adapted for commercial production and installation.

Other and further objects will appear as the description proceeds.

We have illustrated certain preferred embodiments of our invention in the accompanying drawings, in which—

Figure 1 is a fragmentary vertical section through a typical checkerwork;

Figure 2 is a perspective view of one of the filler supporting members;

Figure 3 is a perspective view of one of the filler members;

Figure 4 is a fragmentary horizontal section taken on line 4—4 of Figure 1;

Figure 5 is a fragmentary horizontal section taken on line 5—5 of Figure 1;

Figure 6 is a fragmentary horizontal section taken on line 6—6 of Figure 1;

Figure 7 is a fragmentary horizontal section taken on line 7—7 of Figure 1; and

Figure 8 is a fragmentary horizontal section taken on line 8—8 of Figure 1.

In the drawings, the lowermost courses of brick 11 are formed of usual rectangular brick and supported on the bottom arches of the stove in any usual manner. The filler supporting members 12 are supported on the brick course 11 and placed in the formation best shown in Figure 8. These members 12 have the angularly related meeting surfaces 13 and are spaced apart by the brick 14 which have similar chamfered meeting surfaces 15. The supporting members 12 have their lateral portions 16 formed the full height of the brick and filler brick used in the checkerwork. They have an intermediate cross surface 17 located at half the height of the supporting member and consequently at half the height of the filler brick.

The filler brick 18 shown in Figure 3 have a thickened central portion 19 and ends or edge portions 20 formed to fit into the corners of the square or rectangular openings into which the filler brick are to be fitted.

The lowermost course of filler brick rests upon the surfaces 17 of the supporting members 12. The checkerwork immediately above the bottom course is shown in cross section in Figure 7 and consists of the filler brick 18, the full size brick 21 and the part size brick 22. In order that it may be clear as to just how the several horizontal sections of Figures 4 to 8 are superposed, points have been marked A and it will be understood that the points marked A will be superposed throughout the construction.

The construction as shown in Figure 6 is formed of the filler brick 18, full size brick 21 and part size brick 22, but with the brick placed in different relation to that in which

they are shown in Figure 7. By comparison of the points marked A of these two figures, it will be apparent that each full size brick 21 of Figure 6 extends across between and rests upon the part size brick 22 in Figure 7. The part size brick 22 of Figure 6 are at right angles to and placed upon the part size brick 22 of Figure 7, extending also so as to rest on the adjacent ends of the lower full size brick 21. In the construction shown, the filler brick 18 in Figure 6 are superposed on the filler brick 18 of Figure 7.

Referring now to the form of construction shown in Figures 4 and 5, these are made up of the full size brick 21 and the filler brick 18. The full size brick 21 are so placed as to form square passageways for the reception of the filler brick 18. These filler brick 18 divide the square passageways into the smaller approximately triangular passageways 23. The form of construction shown in Figure 4 is similar to that of Figure 5, with the exception that the brick 21 in Figure 4 break joint with the lower brick 21 of Figure 5, and the filler brick 18 of Figure 4 are placed at right angles to the filler brick 18 of Figure 5. It will be noted that the various forms of brick are all of the same height so that the filler brick 18 break joint in the vertical direction with all of the sets of rectangular brick 21 and 22. This breaking of joints between the filler and main brick gives the construction stability against lateral displacement.

It will also be noted from consideration of Figures 4 to 7, that the various brick 21 and 22 break joint with each other in successive layers in the horizontal direction, which gives the structure stability in this direction.

By a consideration of the superposed points A of Figures 4 to 7, it will be apparent that the substantially triangular openings 23 of Figures 4 and 5 register with smaller portions of larger openings in Figures 6 and 7. Thus when the various layers of these four figures are superposed there is provision of cross passages between adjacent vertical passages in one direction in the form of construction shown in Figure 6, and in the opposite direction in the form of construction shown in Figure 7. Thus the blocking of any passage at any given point does not render that portion of the checkerwork useless throughout the height of the stove, as ample provision is made for the by-passing of the gases from one passage to another to get by any obstruction.

It will be understood that the showing of Figure 1 is diagrammatic in character and that large numbers of adjacent courses of brick may be similar in character as the usual structure will contain many times the number of courses shown in the figure. The location of the courses such as shown in Fig-

tures 6 and 7, where there is cross communication between adjacent flues, may be modified as desired, these being placed at different points throughout the height of the structure. It will be further understood that the filler brick shown in Figure 3 may be made of different thicknesses, the thicker brick being used in lower portions of the structure.

10 We have shown certain preferred embodiments of our invention by way of illustration, but it is capable of change and modification to meet varying conditions and we contemplate such changes and modifications 15 as come within the spirit and scope of the appended claims.

We claim:

1. A checkerwork construction, comprising a plurality of rectangular brick built up 20 to form vertical flues, certain of the brick being shorter than others in horizontal length and having their ends spaced from adjacent brick whereby cross passages are formed between certain of the vertical flues.

25 2. A checkerwork construction, comprising a plurality of rectangular brick built up in horizontal courses to form vertical flues, the brick breaking joint horizontally, and a vertical series of filler brick in certain 30 of the flues, said filler brick breaking joint vertically with the rectangular brick.

3. A checkerwork construction, comprising a plurality of rectangular brick built up in horizontal courses to form vertical flues, 35 said brick being built to form cross passages connecting certain of the vertical flues, and a vertically extending continuous series of filler brick in certain of the flues.

4. A checkerwork construction, comprising 40 a plurality of rectangular brick built up in horizontal courses to form vertical flues, said brick being built to form cross passages connecting certain of the vertical flues, and a vertically extending continuous series of 45 filler brick in certain of the flues, the filler brick breaking joint vertically with the main checker brick.

Signed at Chicago, Illinois, this 13th day of July, 1929.

50 JOHN P. GRILLI.
HARRY L. WETHERBEE.
